SPRING FILLED CUSHION

Lewis Larsen and Emil S. Madsen, Menominee, Mich., assignors to Heywood-Wakefield Company, Gardner, Mass., a corporation of Massachusetts

Application March 12, 1948, Serial No. 14,608

3 Claims. (Cl. 155—181)

1

Cross reference is hereby called to applicants' co-pending application Serial No. 407,244, filed February 1, 1954, entitled Method of Making Spring Filled Cushions, which claims the method.

This invention relates to improvements in spring filled cushions and method of making the same and it consists of the matters hereinafter described and more particularly pointed out in the appended claims.

The cushions, with which the invention is more especially concerned, are of the kind including a spring assembly having top and bottom border frames between which the springs are disposed, a padding on the top of the assembly and a covering for the top and sides and ends thereof. Such cushions are used as the seats of certain kinds of chairs, as for instance, theatre chairs.

One of the objects of the invention is to provide a strong, light-weight, spring-filled cushion, which is comfortable to sit upon, is durable and will not break down in use.

Another object of the invention is to provide a cushion of this kind which includes no wood in its construction.

Also, it is an object of the invention to provide a cushion of this kind wherein the cover is attached to the spring assembly without the use of tacks or other fastening elements.

Furthermore, it is an object of the invention to provide a cushion of this kind, wherein the cover is so applied to the spring assembly that it may be readily removed for repair or for renewal, as the case may be.

Again, it is an object of the invention to provide in a cushion of this kind an arrangement of parts whereby the boxing for the cover is under tension to draw the same over the edge of the supporting member of the spring assembly, evenly about the periphery thereof so that the cover is free of wrinkles or folds which would detract from its appearance.

A further object of the invention is to provide a novel method of applying a cover to the assembly without the necessity of tacks and the like and which may be carried out by persons having no special skill in this kind of work.

The above mentioned objects of the invention, as well as others, together with the advantages thereof, will more fully appear as the specification proceeds.

In the drawing:

Fig. 1 is a perspective view of a spring filled cushion in the form of a seat for a theatre chair, embodying the preferred form of the invention, parts thereof being shown as broken away better to show the interior construction thereof.

2

Fig. 2 is a bottom view of the cushion appearing in Fig. 1, on a scale somewhat enlarged over that of said Fig. 1.

Fig. 3 is a vertical detail fragmentary sectional view through a bottom portion of the cushion as taken on the line 3—3 and on a scale enlarged over that of Fig. 1.

Fig. 4 is a perspective view of the covering for the cushion in an inverted condition and more particularly illustrates the same in its condition before the spring assembly is applied thereto and shows the hoop in the hem of the boxing in its opened or extended condition and before the ends of the hoop have been joined together.

Fig. 5 is a detail perspective view of a fragment of the boxing of the cover on a scale enlarged over that of Fig. 4 and shows the manner in which the open ends of the hoop are joined or connected to afford the continuity of the hoop when in the hem of the boxing.

Fig. 6 is a front to rear vertical sectional view through parts making up the cushion when disposed in an inverted condition and after the spring assembly and its padding has been disposed in the cover as an initial step in the assembly thereof.

Fig. 7 is a view similar to Fig. 6 after the spring assembly has been placed in compression with the hoop containing hem disposed in a position permitting a joining of the ends of the hoop to constrict the hem so that it may be disposed, at least in part, within the peripheral edge of the supporting base or frame of the spring assembly to secure the cover thereto.

Referring now in detail to that embodiment of the invention illustrated in the drawings, the improved cushion includes a spring assembly comprising a bottom border frame 10, a top border frame 11, interposed upholstery springs 12—12 and a top padding 13. The bottom border frame 10, which forms the main support for the cushion, is substantially rectangular in shape and is made of angle bar with its horizontal flange 14 facing inwardly and with its vertical flange 15 facing downwardly, as best appears in Figs. 1 and 3. Fixed to and extending from the front to the rear of the frame are laterally spaced metallic straps 16 to which the bottom ends of rows of said springs 12—12 are suitably attached for support.

The top border frame is preferably made of wire and is set slightly forwardly of the bottom frame. The springs 12 are of the conical type and have their larger diameter ends disposed in the plane of the top border frame. The top ends of said springs are secured to each other and to

the top frame in a conventional manner. The padding 13 rests upon the top ends of said springs and said frame 11 and marginal parts of this padding depend below the frame, as best appears in Fig. 1.

The covering for the cushion is indicated as a whole by the numeral 17 and best appears in its inverted position in Fig. 4. It may be made of a fabric or the like, such as used conventionally in coverings for seats. This covering is tailored for the assembly and it includes a top material 18, front and rear boxing portions 19 and 20 respectively and side boxing portions 21-21.

The bottom margin of the boxing portions mentioned are formed to provide a hem 22 in which is enclosed an open ended hoop 23 made of relatively stiff wire, and which hoop is provided at its ends with open eyes 24-24 adapted for a hooked engagement with each other to act as a continuous or closed hoop. The hem mentioned is made by means of a sewing machine. In the tailoring of the cover, the operator takes the hoop in its open ended or extended position and folds the bottom margins of the boxing portions thereof just prior to the stitching and whereby the hoop is confined within the hem, with its eyes spaced apart and exposed at the center of the rear boxing portion 20, as best appears in Fig. 4.

When the covering 17 has been hemmed to confine the open ended hoop as described, the hoop expands laterally, that is the sides of the hoop tend to spread and space the eyes 24 a suitable distance apart. In this condition the hem of the boxing portion has such an area that the spring assembly as a whole may be disposed within the same through the open end of the covering as defined by the hem.

In making the application, the covering is disposed in the inverted position shown in Fig. 4, upon a suitable support 25, with the top covering material 18 engaged face down thereon, as best appears in Fig. 6. With the covering arranged in this condition, the spring assembly as a whole is turned bottom side up and is inserted into the covering so that the padding 13 rests upon the top material and the boxing portions 19-20 and 21-21 are disposed in a generally upright position in association with the front, the rear and the sides of the assembly, as best appears in Fig. 6. At this time the hem 22 of the covering material is disposed in approximately the plane of the frame 10.

Thereafter pressure is applied to the now upwardly facing bottom of the assembly to compress the same and reduce its overall height from top to bottom. This compression force may be produced by a pressure actuated member 26, acting in a direction perpendicular to the support 25 and which member 26 appears in Fig. 7.

When the spring assembly is in compression, its height is reduced to one less than the height of the boxing portions 19, 20 and 21-21 so that the hem 22 with the open hoop 23 therein is disposed a suitable distance above the frame 10, as best appears in Fig. 7. Thus the hem is disposed in a position wherein it may be manipulated to be drawn over and inwardly of the flange 15 of the frame 10 to overhang the same, after which the open eyes 24 of the hoop are disposed in such close relationship that they may be hooked together as a connection, as appears in Fig. 5 to close the hoop. In this condition of the hem with the hoop disposed therein, said hem is constricted in its outline area and is located inwardly of the

flange 15 of the bottom frame, as best appears in Fig. 2.

Thereafter, pressure member 26 is elevated to release the compression on the spring assembly, which then expands. As the hem 22, with the closed hoop therein, is disposed within the outline area of the flange 15 of the frame and cannot escape therefrom, the expansion of the spring assembly tensions the boxing portions 19, 20 and 21-21, and draws the entire cover into a good smooth, snug fitting engagement upon the assembly free of folds or wrinkles. By reason of the inturned hem and hoop therein, the spring assembly cannot return to its normal expanded condition, but is held in a slightly compressed condition, which continually acts to keep the covering in a good fitting relation upon the assembly.

When a cushion of this kind is employed as the seat for a theatre chair, it is subjected to a continuous hard use and the covering is often torn or soiled to such an extent as requires a replacement thereof.

To remove a torn or soiled covering for the replacement by a new one, the cushion as a whole, after its removal from its associated chair, is again placed under compression so as to be in the condition of Fig. 7 and at which time the eyed ends 24-24 of the hoop 23 can be and are released or disconnected from each other. This permits the hem to be returned to the position appearing in Fig. 6, at which time it is free of tension. After the member 26 has been removed from the position mentioned, the covering as a whole may be "peeled" from the assembly and a new covering applied in the manner before described.

While in describing the invention we have referred in detail to the form, construction and arrangement of the parts embodied therein, as well as one way in which the covering and assembly are relatively applied, the same is to be considered only in the illustrative sense and therefore we do not wish to be limited thereto except as may be specifically set forth in the appended claims.

We claim as our invention:

1. A unitary assembly for a chair seat comprising a vertically resilient cushion including a top portion, a bottom border frame for the assembly having a substantially vertically downward extending flange having a bottom edge, a covering including a boxing enclosing said top portion and the periphery of said cushion and said frame, a portion of said boxing extending downwardly in the general direction of said flange and inwardly across said bottom edge thereof and terminating as a margin, a hoop secured to said margin and having ends, and means detachably connecting said ends together and constricting the outline of said hoop and said margin to one less than that of said flange whereby said covering is stretched around the cushion.

2. A unitary assembly for a chair seat comprising a vertically resilient cushion including a top portion, a bottom border frame of angle bar for the assembly including a substantially downwardly extending vertical flange and an inwardly extending top horizontal flange, said vertical flange having a bottom edge, a covering including a boxing covering said top portion and the periphery of said cushion and said frame, a portion of said boxing extending downwardly in the general direction of said vertical flange and inwardly across said bottom edge thereof and ter-

minating as a margin, a hoop secured to said margin and having ends, and means detachably connecting said ends together and constricting the outline of said hoop and said margin to one less than that of said flange whereby said covering is stretched around the cushion.

5

3. A unitary assembly for a chair seat comprising a border frame including a substantially vertically downward extending flange having a bottom edge, spring means supported upon said border frame and supporting a padding to coact therewith in forming a cushion, a covering including a boxing enclosing the top of said cushion as well as the periphery thereof and the periphery of said spring means and said frame, a portion of said boxing extending downwardly in the general direction of said flange and inwardly across said bottom edge thereof and terminating as a margin, a hoop secured to said margin and having ends and means detachably connecting 20 said ends together and constricting the outline

of said hoop and said margin to one less than that of said flange whereby said covering is stretched around the cushion.
